PRESSURE CASTING MACHINE

Nathan Lester, Cleveland Heights, Ohio, and William M. Lester, Leominster, Mass., assignors to Lester Engineering Company, Cleveland, Ohio, a corporation of Ohio

Application July 3, 1935, Serial No. 29,638

16 Claims. (Cl. 22—68)

The present invention relates to an apparatus for casting metal under relatively high pressure wherein a charge of metal is forced from a pressure chamber into a permanent mold cavity defined by a pair of separable die blocks.

The general object and nature of the invention is to transfer a measured charge of metal, sufficient to completely fill the mold cavity and gate, from a melting pot, to a pressure chamber, and to eject a quantity of metal therefrom into the mold cavity without exposing such metal to the atmosphere and without entrapping any air or air bubbles in the casting charge.

A further object of the invention is to provide means for ejecting surplus metal or solidified "slugs" from the charging chute through which the molten metal is transferred into the pressure chamber. Another object of the invention is to provide a measuring plunger adapted to vary the volume capacity of the pressure chamber and to maintain the casting charge in a compact mass until it is in position to enter the mold cavity. A further object is to provide means for automatically regulating the position and movement of such measuring plunger.

Still another object of the invention is to provide a melting pot and furnace structure which can be quickly and easily removed and replaced from the casting machine assembly. Additional objects and advantages shall become apparent during the following description.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Fig. 1 is an elevational view in section of the assembly of the machine embodying the principle of our invention; Fig. 2 is an enlarged sectional view of the charging chute and pressure chamber taken upon a plane normal to that of Fig. 1 and substantially along the line 2—2 thereof; Fig. 3 illustrates an alternative form of construction for the parts shown in Fig. 2; Fig. 4 is an enlarged fragmentary sectional view taken upon a plane normal to that of Fig. 1 and substantially along the line 4—4 thereof, showing the connection between the measuring plunger shaft and the auxiliary resistance shaft.

Now referring more particularly to Fig. 1, the pressure casting machine shown therein consists of a supporting base 1 carrying the horizontal tie rods 2, the end tie plate 3, and the upper tie rods 4 (only one each of the tie rods 2 and 4 being shown). A die plate 5 is carried by the right hand end of the tie rods 2 and 4, or upon the end opposite to that of the tie plate 3. A movable die plate 6 is also carried upon the intermediate portion of the tie rods 2 and 4. The die plates 5 and 6 are adapted to carry the die blocks 7 and 8 respectively, whose opposed faces define a mold cavity 9.

Toggle link mechanism indicated generally by the numeral 10, together with the hydraulic actuating cylinder 11, connects the end tie plate 3 to the movable die plate 6. The die plate 6 is carried upon the movable plate 12 by means of a screw jack mechanism 13 whereby the position of the die plate 6 with respect to the movable plate 12 may be variably regulated. The last described mechanism for actuating the die plate 6 is not claimed as novel in the present invention, since it is embodied in the subject matter and explained in detail in the copending application of William M. Lester, Serial No. 5,438, filed February 7, 1935.

A pressure casting chamber or cylinder 15 is mounted in the die plate 5. A pressure plunger 16 enters the right hand end of the casting cylinder 15 and is connected to the piston rod 17 leading to the hydraulic pressure cylinder 18. Flexible connections 19 and 20 communicate with the interior of the pressure plunger 16, which is hollow and are for the purpose of circulating a cooling medium such as water or oil within the interior of the plunger 16. The hydraulic cylinder 18 is mounted upon the base 1 by means of a supporting bracket 21.

A charging chute 24 leads from the pressure casting cylinder 15 to the metal melting pot 26. The melting pot 26 is in turn mounted in a heating furnace structure 27. The melting pot 26, the heating furnace 27 and its housing 28 is mounted upon the supporting rollers 29 whereby the melting pot and furnace can be rolled laterally, that is, in a direction normal to the plane of Fig. 1, from under the casting machine, merely by removing the charging chute 24. In this manner, a melting pot and furnace which needs repair may be very easily removed and replaced in position with respect to the casting machine, or the melting pot and furnace containing a different composition of metal may be conveniently substituted when desired.

5 The upper portion 30 of the charging chute has a recess for the reception of the rectangular exterior wall 31 of the pressure cylinder 15. A removable cap 32 holds the charging chute portion 30 in position with respect to the casting cylinder 15. Suitable studs 33, 33 fasten the cap 32 to the face of the charging chute portion 30. The upper end of the charging chute passage 25 intersects and communicates with the interior of 10 the casting cylinder 15, as indicated at 34.

15 For the purposes of convenient fabrication, and machine practice, the rectangular cylinder housing 31 may be made into two pieces joined together along the parting line 35 in the same plane as the axial center of the charging chute 10 passage.

20 A vacuum passage 36 leads from the upper end of the charging chute passage 25 to the port 37 which in turn is connected to the vacuum conduit 38. The vacuum conduit 38 leads to a 25 vacuum pump or motor (not shown). The vacuum passage 36 is of cylindrical form and a plunger or piston 39 is mounted therein. The upper end of the piston 39 carries a gear rack 40 adapted to be engaged by the gear segment 41 on the end of the lever 42. The lever 42 is pivoted at the point 43 and carried by the housing 44 which in turn is threadably mounted as 45 at 46 to the upper end of the charging chute 24. The housing 44 also serves as a guide for the reciprocal movement of the enlarged upper end 46 of the piston 39. A connecting rod 47 connects 50 the outer end of the lever 42 to the movable tie plate 12. Thus movement of the die plate 6 and of the movable plate 12 operates to oscillate the lever 42 about its pivot point 43 and to thereby raise and lower the piston 39. When the piston 39 reaches its uppermost position, as shown in Fig. 2, the vacuum passage port 37 will be opened and the vacuum placed in communication with the 55 charging chute passage 25 and the interior of the casting cylinder 15. On the downward movement of the piston 39, the vacuum passage port 37 will be closed and continued downward movement will extend the piston 39 into the vacuum passage 36 and the upper end of the charging chute passage 25 whereby excess metal which might have frozen out in the upper end of the 60 passage 25 and in the passage 36 will be forcibly ejected and dropped back into the melting pot 26.

55 For the purpose of conveniently removing and replacing the charging chute, the alternative form of construction as shown in Fig. 3 may be employed. In Fig. 3, the charging chute is made in the form of a separable element 24' which 60 threadably engages the housing 30' as at 48. A hexagonal portion 49 on the outer surface of the charging chute 24' is for the reception of a wrench whereby the chute 24' may be conveniently screwed on or unscrewed from the housing 30'.

65 Directing attention to Fig. 1, a measuring plunger 50 extends through the die blocks 7 and 8 and is adapted to enter the left hand or discharge end of the casting cylinder 15. The end of the measuring plunger 50 and the end of the pressure plunger 16 thus define end walls in the pressure cylinder 15. The left hand or outer end 51 of the measuring plunger 50 is 70 journalled in the movable die plate 6 and has a gear rack which meshes with the gear teeth on the transverse shaft 52. The shaft 52, as will be best seen in Fig. 4, is journalled in a recess in the die plate 6 and held therein by 75 means of the cap screw 53. The lower end of the

transverse shaft 52 meshes with a gear rack 53 on the end of the auxiliary shaft 54. The auxiliary shaft 54 is carried by downwardly projecting bores 55 and 56 extending from the die plate 6 and the movable plate 12 respectively. 5

10 It will thus be seen that the measuring plunger shaft 51 and the auxiliary shaft 54 are so connected by the cross shaft 52 that movement of either one in a given direction will be transmitted into movement of the other in an opposite direction. For example, when the measuring plunger 50 and its shaft 51 are moved in a left hand direction with respect to Fig. 1, the cross connecting shaft 52 will be rotated in such a direction as to transmit the left-hand movement of 15 the shaft 51 into a right-hand movement of the shaft 54.

15 The left hand end of the shaft 54 is connected to the adjustable, threaded spindle or shaft 60 by means of the sleeve 61 and a friction packing gland composed of the bushing 62 and the friction packing material 63. The shaft 60 threadably engages an internally threaded sleeve 64, the latter being fixed to the base 1. The outer end of the shaft 60 is squared as at 65 for the reception of a suitable rotating tool or wrench whereby the position of the shaft 60 may be adjustably regulated with respect to the fixed base 1. 20

25 The operation of the automatic measuring plunger 50 and its above described connecting mechanism is as follows:

30 When the casting cylinder 15 is filled with molten metal by the action of the vacuum through the passage 36 and through the charging 35 chute passage 25, the pressure plunger 16 is then moved in a left hand or discharging direction. Compression of the metal charge in the cylinder 15 tends to force the measuring plunger 50 in a left hand direction, or outwardly with respect to the cylinder 15. Such left hand movement of the measuring plunger 50 and its shaft 51 is transmitted through the cross connecting shaft 52 to the auxiliary shaft 54, tending to draw the latter in a right hand direction. But 40 the right hand movement of the shaft 54 is resisted by virtue of the friction packing 63 in the sleeve 61. In this manner, the left hand or outward movement of the measuring plunger 50 with respect to the casting cylinder 15 is resisted, but the pressure exerted by the pressure plunger 16 is sufficient to overcome such resistance until the shoulder 66 on the measuring plunger 50 abuts against the face of the die plate 6. At 45 this point the right hand end of the measuring plunger 50 has cleared the sprue opening 67 to the mold cavity 8, as indicated by the dotted line 68 and, further movement of the pressure plunger 16 forces the metal charge into the mold cavity 8. At the next stage of operations, when 50 the movable die plate 6 is moved in a left hand direction in order to open the die blocks 7 and 8, such movement will tend to rotate the cross connecting shaft 52 in a counterclockwise direction as viewed in Fig. 1; but since the shoulder 55 66 abuts against the face of the die plate 6, such counterclockwise rotation will not be possible and the shaft 52 will therefore become locked, with the result that the position of the shaft 54 with respect to the movable die plate 6 is 50 also locked. Hence left hand movement of the die plate 6, due to the locking of the cross shaft 52 will be transmitted into left hand movement of the shaft 54, into the space 69 between its left hand end and the end of the threaded shaft 75 70 75

68. On closing movement of the die blocks 7 and 8, or on right-hand movement of the die plate 6, the resistance exerted by the friction packing 63 will tend to hold the shaft 54 in place with the result that the cross shaft 52 will be rotated in a clockwise direction with respect to Fig. 1, and thereby move the shaft 51 and measuring plunger 58 in a right hand direction and back into its original starting position, as shown in Fig. 1.

10 In order to variably regulate the initial starting position of the measuring plunger 58, and incidentally, of course, to vary the volume capacity of the cylinder 15, the position of the threaded shaft 60 with respect to the fixed base 1 is varied. Thus, if the threaded shaft 60 is moved in a left hand direction, such movement will be transmitted through the shaft 54, the cross shaft 52 to the measuring plunger 58 with the result that the latter will move further into the casting cylinder 15 and thereby reduce the volume capacity of the latter. Conversely, right hand movement of the threaded shaft 60 will move the measuring plunger 58 in a left hand direction or outwardly with respect to the cylinder 15 resulting in a greater volume capacity of the latter. In this manner, the metal casting charge received and delivered by the casting cylinder 15 may be adjustably varied as required and demanded.

15 It should be noted that the lower end of the charging chute 24 extends below the level 78 of the metal in the melting pot 26. An inert material spread over the top of the metal in the melting pot 26 serves to seal the metal from atmospheric contact. Thus, it will be seen that the above described pressure casting machine accomplishes the functions and results of receiving a measured quantity of molten metal from the melting pot without exposing the metal to oxidation by contact with the atmosphere, transfers such measured charge of metal in a compact body to the opening into the mold cavity, and also ejects any solidified or frozen out slug from the feed passage into the casting cylinder back into the melting pot. The above described machine also effects a convenient means for adjustably varying the capacity of the casting cylinder, and correspondingly, the amount of the measured metal charge.

20 The above described preferred embodiment of our invention of course discloses the use of vacuum pressure for transferring the molten metal from the melting pot 26, through the charging chute 24 and to the pressure cylinder 15. However, it should be equally well understood that an equivalent pressure means can be utilized without transcending the spirit of the invention. For example, instead of a vacuum communicating with the upper end of the charging chute passage 25, the top of the melting pot 26 could be hermetically sealed and a greater than atmospheric pressure introduced therein whereby the molten metal would be forced up through the charging chute 24 and into the interior of the pressure casting cylinder 15.

25 Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

75 1. In a pressure casting machine of the type

having a melting pot, a pressure chamber for receiving and discharging fluid metal under pressure, and a pressure passage connected to said chamber for transferring fluid metal thereto from the melting pot, the combination of means for ejecting excess metal from said passage back into said melting pot.

2. In a pressure casting machine of the type having a melting pot, a pressure chamber for receiving and discharging fluid metal under pressure, and a pressure passage connected to said chamber for transferring fluid metal thereto from the melting pot, the combination of means for opening and closing said passage and also for ejecting excess metal from said passage back into said melting pot.

3. In a pressure casting machine of the type having a melting pot, a pressure chamber for receiving and discharging fluid metal under pressure, and a vacuum passage connected to said chamber for drawing fluid metal thereto from the melting pot, the combination of means for measuring the amount of metal discharged from said chamber, and means for ejecting excess metal from said passage back into said melting pot.

4. In a pressure casting machine of the type having a melting pot, a pressure chamber for receiving and discharging fluid metal under pressure, and a vacuum passage connected to said chamber for drawing fluid thereto from said melting pot, the combination of means movable within the interior of said chamber for resisting the discharge of metal therefrom and also for varying the volume capacity of said chamber, and means for ejecting excess metal from said passage back into said melting pot.

5. In a pressure casting machine of the type having a melting pot, a pressure chamber for receiving and discharging fluid metal under pressure, and a vacuum passage connected to said chamber for drawing fluid thereto from said melting pot, the combination of means movable with the interior of said chamber for resisting the discharge of metal therefrom and also for varying the volume capacity of said chamber, and means for opening and closing said passage and also for ejecting excess metal from said passage back into said melting pot.

6. In a pressure casting machine of the type having a melting pot, separable die blocks defining a mold cavity, means for opening and closing said blocks, and a pressure cylinder and plunger therein for discharging fluid metal into said cavity, the combination of a second plunger carried by one of said blocks and movable into and out of the discharge end of said cylinder, the pressure generated by said first-named plunger being adapted to move said second plunger outward with respect to said cylinder, the closing movement of said blocks being adapted to move said second plunger inwardly with respect to said cylinder, and means for adjustably regulating the extent of such inward movement.

7. In a pressure casting machine of the type having a melting pot, separable die blocks defining a mold cavity, means for opening and closing said blocks, and a pressure cylinder and plunger therein for discharging fluid metal into said cavity, the combination of a second plunger carried by one of said blocks and movable into and out of the discharge end of said cylinder, means for stopping the outward movement of said second plunger at a point where its end

has cleared the entrance to said cavity, the pressure generated by said first-named plunger being adapted to move said second plunger outwardly with respect to said cylinder, the closing movement of said blocks being adapted to move said second plunger inwardly with respect to said cylinder, and means for adjustably regulating the extent of such inward movement.

8. In a pressure casting machine of the type having a melting pot, separable die blocks defining a mold cavity, means for opening and closing said blocks, and a pressure cylinder and plunger therein for discharging fluid metal into said cavity, the combination of a second plunger carried by one of said blocks and movable into and out of the discharge end of said cylinder, means for stopping the outward movement of said second plunger at a point where its end has cleared the entrance of said cavity, means for resisting the outward movement of said second plunger with respect to said cylinder, the pressure generated by said first-named plunger being adapted to move said second plunger outwardly with respect to said cylinder, the closing movement of said blocks being adapted to move said second plunger inwardly with respect to said cylinder, and means for adjustably regulating the extent of such inward movement.

9. In a pressure casting machine of the type having a melting pot, a pressure cylinder and a plunger therein, and a charging chute communicating between said pot and said cylinder, the combination of a vacuum passage terminating at a point in alignment with the upper end of said chute and adjacent the juncture of said chute and of said cylinder, and means for ejecting excess metal from said chute back into said melting pot.

10. In a pressure casting machine of the type having a melting pot, a pressure cylinder and a plunger therein, and a charging chute communicating between said pot and said cylinder, the combination of a vacuum passage terminating at the juncture of said chute and of said cylinder, and a piston movable in said passage for opening and closing the latter, said piston being also adapted to eject excess metal from said chute back into said melting pot.

11. In a pressure casting machine of the type having a melting pot, separable die blocks defining a mold cavity, means for opening and closing said blocks, a melting pot, a pressure cylinder and a plunger therein, and a charging chute communicating between said pot and said cylinder, the combination of a vacuum passage terminating adjacent the juncture of said chute and of said cylinder, a piston movable in said passage for opening and closing the latter, said piston being also adapted to eject excess metal from said chute back into said melting pot, and means operable by the movement of said die blocks for actuating said piston.

12. In a pressure casting machine of the type having a melting pot, separable die blocks defining a mold cavity, means for opening and closing said die blocks, a pressure cylinder and plunger therein for discharging fluid metal into said cavity, and a charging chute communicating between said pot and said cylinder, the combination of a second plunger carried by one of said blocks and movable into and out of the discharge end of said cylinder, the pressure generated by said first-named plunger being adapted to move said second plunger outwardly with respect to said cylinder, and the closing move-

ment of said blocks being adapted to move said second plunger inwardly with respect to said cylinder, a melting pot, a vacuum passage terminating adjacent the juncture of said chute and of said cylinder, and means for ejecting excess metal from said chute back into said melting pot.

13. In a pressure casting machine of the type having a melting pot, separable die blocks defining a mold cavity, means for opening and closing said blocks, a melting pot, a pressure cylinder and a plunger therein, and a charging chute communicating between said melting pot and said cylinder, the combination of a second plunger carried by one of said blocks and movable into and out of the discharge end of said cylinder, the pressure generated by said first-named plunger being adapted to move said second plunger outwardly with respect to said cylinder, and the closing movement of said blocks being adapted to move said second plunger at a point where its end has cleared the entrance to said cavity, means for resisting the outward movement of said second plunger with respect to said cylinder, means for adjustably regulating the extent of such inward movement, a vacuum passage terminating adjacent the juncture of said chute and of said cylinder, and a piston movable in said passage for opening and closing the latter, said piston being also adapted to eject excess metal from said chute back into said melting pot.

14. In a pressure casting machine of the type having separable die blocks defining a mold cavity, means for opening and closing said blocks, a supporting base, and a pressure cylinder for receiving and discharging fluid metal into said cavity, the combination of a plunger movable into and out of the discharge end of said cylinder for varying the volume capacity thereof, the outer end of said plunger being slidably supported by one of said blocks, a shaft parallel to said plunger, a second shaft having its axis normal to said plunger and said first-named shaft, rack and gear means connecting said second-named shaft to said plunger and said first-named shaft whereby movement in one direction of said plunger is transmitted to movement in an opposite direction of said first-named shaft, and friction detent means slidably connecting said first-named shaft to said supporting base, and means for adjustably regulating the position of said friction detent means.

15. In a pressure casting machine of the class wherein fluid metal is fed through one of a pair of separable die blocks from a pressure chamber carried by said one of the pair of die blocks, and a plunger in said chamber for discharging fluid metal from said chamber under pressure, the combination of means independent of said plunger and carried by the other of said pair of die blocks for varying the volume capacity of said chamber.

16. In a pressure casting machine of the class wherein fluid metal is fed through one of a pair of separable die blocks from a pressure chamber carried by said one of the pair of die blocks, and a plunger in said chamber for discharging fluid metal from said chamber under pressure, the combination of means independent of said plunger and movable within the interior of said chamber for resisting the discharge of metal therefrom and also for varying the volume capacity of said chamber, said means being carried by the other of said pair of die blocks.

NATHAN LESTER.

WILLIAM M. LESTER. 75
